CLAIM

The ornamental design for a candle jar lid, as shown and described.

DESCRIPTION

FIG. 1 is a top view of the candle jar lid according to the present invention;

FIG. 2 is an underside view thereof;

FIG. 3 is a perspective view thereof;

FIG. 4 is a side view thereof, all other sides being identical; and,

FIG. 5 is a perspective view thereof, shown in an environment of use with an exemplary candle jar.

The broken lines shown in FIG. 2 are shown for the purpose of illustrating parts of the article that form no part of the claim.

(Continued)

The broken lines in FIG. 5 are shown for the purpose of illustrating environmental subject matter of an exemplary candle jar and form no part of the claimed design.

1 Claim, 5 Drawing Sheets
